Primary Examiner — Philip S Hyder*Assistant Examiner* — Roselynne Cody(74) *Attorney, Agent, or Firm* — Breiner & Breiner, L.L.C.(57) **CLAIM**

The ornamental design for a demolition tool, as shown and described.

DESCRIPTION

FIG. 1 is a side view of the demolition tool in a first position with the talons open;

FIG. 2 is side view of the demolition tool in a second position with the sleeve lowered and the talons closed;

FIG. 3 is a top view of the demolition tool of FIG. 1;

FIG. 4 is a bottom view of the demolition tool of FIG. 1;

FIG. 5 is a first end view of the demolition tool of FIG. 1; and, FIG. 6 is a second end view of the demolition tool of FIG. 1. The jagged lines separating the two portions of the shaft indicate that any portion of the article beyond what is shown forms no part of the claim.

1 Claim, 2 Drawing Sheets(56)
